UNITED STATES PATENT OFFICE

1,983,633

TYPOGRAPHICAL COMPOSING MACHINE

William J. Mulroy, Woodhaven, N. Y., assignor
to Mergenthaler Linotype Company, a corpora-
tion of New York

Application June 1, 1933, Serial No. 673,826

11 Claims. (Cl. 199—18)

This invention relates to typographical machines, such as linotype machines of the general organization represented in Letters Patent of the United States to O. Mergenthaler No. 436,532, wherein circulating matrices are released from a magazine in the order in which their characters are to appear in print, and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started.

More particularly, it relates to machines of the kind presented in prior Letters Patent Nos. 1,309,416; 1,373,942; 1,433,087; 1,561,244 and 1,561,245, wherein the matrix magazines are arranged side by side or in "tandem" and wherein the matrices are drawn from the different magazines by the manipulation of a single keyboard common to them all.

The present invention is directed to certain improvements in machines of the class stated, as will be fully set forth in the detailed description to follow.

In the accompanying drawings, the improvements have been illustrated merely in preferred form and by way of example, and as applied to the particular style of machine mentioned, but obviously many changes and variations may be made therein, and in their mode of application, which will still be comprised within the spirit of the invention. Further, the improvements are readily adaptable to other forms of typographical machines, such as those that handle types or dies, instead of matrices. Generally speaking, it is to be understood that the invention is not limited to any specific form or embodiment, except insofar as such limitations are specified in the appended claims.

Referring to the drawings:

Fig. 1 is a front elevation of a portion of a linotype machine equipped with the improvements;

Fig. 2 is essentially a vertical section taken through the keyboard devices associated with the main magazines, and showing the connections to the auxiliary magazine in inoperative position;

Fig. 3 is a view similar to Fig. 2, but showing the connections to the auxiliary magazine in operative position;

Fig. 4 is a vertical section taken on the line 4—4 of Fig. 2, and looking in the direction of the arrow;

Fig. 5 is a top plan view of a portion of the keyboard devices;

Fig. 6 is a vertical section taken through the escapement devices associated with the auxiliary magazines;

Fig. 7 is a rear elevation of the electrical escapement control devices for the auxiliary magazines; and

Fig. 8 is a view similar to Fig. 3, but showing a modification or alternative embodiment of the invention.

In the machine illustrated, which is given purely by way of example, the matrices X of the regular fonts are stored in two or more superposed main magazines A, while the matrices Z of the supplemental fonts are similarly stored in two superposed auxiliary magazines B, the latter being arranged at the side of or in tandem with the main magazines. The main magazines A are of the customary trapezoidal form, each having its grooved channels (ninety in number) converging toward its lower end and spaced apart to accommodate the smaller matrices of the regular fonts; whereas, the auxiliary magazines B are of plain rectangular shape, each having its grooved channels (thirty-four in number) parallel throughout and more widely spaced apart to accommodate the larger matrices of the supplemental fonts. Cooperating with the magazines, is a common assembler entrance having a main portion C arranged to receive the matrices X from a selected one of the main magazines A, and an auxiliary portion C¹ arranged to receive the matrices Z from a selected one of the auxiliary magazines B, it being observed that both portions C and C¹ discharge the matrices onto an assembling belt C², which delivers them to an assembler C³, wherein they are composed in line. Both the main and auxiliary magazines are movably mounted so that by the operation of suitable magazines shifting mechanism any selected pair may be brought into operative relation to the common assembler entrance. Any of the well known forms of mounting may be employed for this purpose, such as that embodied in the commercial Model 14 machine, but it is preferred to make use of the particular form of mounting shown and described in prior Letters Patent No. 1,459,978 to D. S. Kennedy, which latter form is of such character as to permit the shifting of the magazines without disturbing their operative connection with the distributing mechanism.

Each of the magazines A is provided with matrix releasing escapements of ordinary form (as shown, for example, in Patent No. 1,561,245) 55.

already referred to), one escapement for each channel thereof, and these escapements, or those belonging to the magazines in operative position, are actuated by a set of vertically movable reeds 5 D which act thereon through intermediate pivoted levers (not shown). The auxiliary magazines B are provided with similar escapements E actuated in the same fashion by a second set of vertically movable reeds E² through intermediate 10 pivoted levers E¹. According to the present invention, the two sets of actuating reeds are operated by two corresponding sets of power driven elements under the control of a single keyboard G¹, means being provided for shifting the control 15 of the proper finger keys of said keyboard to either set of power driven elements, so as thus to effect the release of matrices from the operative main or auxiliary magazine, as desired.

The power driven elements for the main set of 20 reeds D are of well known construction, comprising (Figs. 2 and 3) two banks or series of pivoted yokes or levers D³, rotary cams or eccentrics D⁴ journaled thereon, two power driven rolls D⁵, and two rows of trip dogs D⁶, all operating in the 25 usual way. The power driven elements for the auxiliary set of reeds E² are of the same construction, comprising (Fig. 6) a single bank or series of pivoted yokes or levers E³, rotary cams or eccentrics E⁴ journaled thereon, a single 30 power driven roll E⁵, and a single row of trip dogs E⁶.

When it is desired to draw matrices from the main magazine in operative position, the various finger keys G (ninety in number) are connected 35 through slides D⁷ and their respective trip dogs D⁶ to the main set of cam yokes D³, see Fig. 2. On the other hand, when it is desired to draw matrices from the auxiliary magazine in operative position, the connections between certain of 40 the trip dogs D⁶ and their respective cam yokes D³ is broken by means of a member K which is raised to lift the yokes out of engagement with the trip dogs, see Fig. 3, and at the same time a connection is established between the corresponding 45 slides D⁷ and a similar series of slides E⁷ connected with the auxiliary set of trip dogs E⁶ and cam yokes E³, provision being made to effect the change from the main set of cams and yokes to the auxiliary set, and vice versa, as required.

According to the present invention, the slides 50 E⁷ are actuated by a corresponding series of electro-magnets S under the control of the finger keys G through the slides D⁷ and intermediate electric connections. As best shown in Figs. 6 and 7, the magnets S are mounted side by side in an insulated channeled support S¹ secured to a panel S² which is fastened to the machine rearwardly of the slides E⁷. A corresponding series 55 of levers E⁸ are pivotally mounted in the panel S², one end of each lever being in engagement with a slide E⁷ and the other end normally located above one of the magnets S and serving as an armature which, when attracted by the magnet and rocked about its pivot, raises the slide E⁷ 60 with which it is engaged and thereby trips the corresponding dog E⁶ to throw the associated cam E⁴ into action.

The electric connections between the slides D⁷ and the magnets S comprise a series or bank of 65 contact points or fingers H (see Figs. 2 and 3), individually secured by screws h to a panel H¹ arranged at the back of the keyboard. A corresponding series of contact points H², individually secured to an insulated support H³ by screws h¹, 70 are arranged so that each contacts with one of

the points H². The insulated support H³ carries a conductor plate H⁴, which overhangs the front edge of the support H³ as at h², presenting a continuous surface in alinement with and spaced apart from the front or free ends of the contact points H²; and a single contact point H⁵, secured to the panel H¹ by a screw h³, is arranged to engage at all times with the conductor plate H⁴. A plurality of wires H⁷ lead from the contact points H through a cable h⁴ (Fig. 1) to a series of posts 10 in the form of screws s¹ (Fig. 7) arranged on an insulated panel s, which is fastened to the machine in proximity to the magnets S. The magnets S are connected to the posts s¹ by wires s², and are grounded to the machine by wires s³ 15 leading to posts s⁴ arranged on the panel S². As indicated in Fig. 3, the contact point H⁵ is connected with a source of electric current supply, as by the wire H⁸, and the circuit completed by grounding the wire H⁹ to a suitable part of the 20 machine. Of course, the wiring as shown in the drawings is merely diagrammatic, and obviously the circuit may be established as desired.

For effecting the shift from the main magazine in operative position to the auxiliary magazine in 25 operative position, the member K (see Figs. 2, 3 and 5) is formed with lateral flanges K¹ to engage the cam yokes D³ and raise them from engagement with the trip dogs D⁶, as already stated, and the support H³ which carries the contact 30 points H² is mounted for fore-and-aft movement to bring the front or free ends of the contacts H² into vertical alinement with insulated bumpers H¹⁰ on the slides D⁷.

To raise the member K and shift the support H³, 35 there is employed a finger key J pivotally mounted as at J¹ on a support J² secured to a bracket G² at the side of the keyboard G¹. The finger key J is of the broken-lever type, comprising arms J³ and J⁴ cooperatively held together by a wire 40 spring J⁵ arranged at the pivot point J¹ and bearing against the arms J³ and J⁴, and which is limited in its action by a bent-over end J⁶ of the arm J³ adapted to engage the top edge of the arm J⁴. Pivotally mounted on the arm J³ as at J⁷, is a 45 locking key J⁸, normally held in the position shown in Fig. 2 by a wire spring J⁹, and being formed with a catch J¹⁰ adapted to engage a retaining lug J¹¹ carried by the bracket J². A tension spring J¹², one end of which is secured to 50 the arm J⁴ and the other end to a pin J¹³ at the side of the keyboard, maintains the finger key J in its normal inactive position shown in Fig. 2.

The rear end of the arm J⁴ (Fig. 5) is connected to a lever arm J¹⁴ by a pin J¹⁵, the opposite end of the lever arm J¹⁴ being pinned fast to a rock shaft J¹⁶ extending transversely of the keyboard and rotatably supported in side frames G² and G³ thereof. The rock shaft J¹⁶ has pinned to it a pair of bell-crank levers J¹⁷ which carry the support H³ bearing the contact points H² (Fig. 4), the levers J¹⁷ being secured to opposite ends of the support H³ by screw bolts J¹⁸ which pass through the levers at their bend. At the free end of each of the levers J¹⁷, there is provided a pin J¹⁹ adapted to engage the underside of the support H³ and limit its movement to inactive 65 position, as will be pointed out hereafter in the description of the operation of the invention.

The member K extends transversely of the keyboard G¹ directly beneath the inner ends of the cam yokes D³ and is supported at opposite ends by a pair of arms k and k¹, the former being mounted on the connecting pin J¹⁵ at the left of the keyboard, and the latter on a similar pin J²⁰ 70

at the right of the keyboard. It will be recalled that the pin J^{15} connects the finger key J to the lever arm J^{14} which is pinned to the rock shaft J^{16} , and hence when the key J is depressed the 5 pin J^{15} is carried upwardly, its upward movement rocking the shaft J^{16} and also being transmitted to the left end of the member K through the arm k . The pin J^{20} , however, on which the arm k' is mounted, is carried by a lever arm J^{21} pinned 10 to the rock shaft J^{16} , so that the elevation of the right hand end of the member K is effected by the rotation of the shaft J^{16} . However, the movement imparted to the opposite ends of the member K is uniform and simultaneous, so that it 15 (the member K) maintains a substantially horizontal position during its vertical movement.

The release of matrices from the main magazine in operative position has already been described, and, moreover, is effected in the ordinary 20 manner well known to those skilled in the art (see Fig. 2). In utilizing the present invention to draw matrices from the auxiliary magazine in operative position, the finger key J is depressed, rocking the shaft J^{16} through the lever arm J^{14} 25 to rotate the bell-crank levers J^{17} and move the support H^3 forwardly to position the free ends of the contact points H^2 directly above the bumpers H^{10} on the slides D^7 (see Fig. 3). The depression of the key J also moves the member 30 K vertically, as already described, the flanges K^1 engaging the inner ends of the cam yokes D^3 and disconnecting them from their respective trip dogs D^6 (see also Fig. 3). In this condition of the parts, depression of one of the affected finger 35 keys G will raise the corresponding slide D^7 , but the corresponding cam D^4 will not be thrown into action because of the disengagement of its supporting yoke D^3 from the respective trip dog D^6 . Instead, the bumper H^{10} on the slide D^7 will strike 40 the free end of the contact point H^2 , which has been moved into vertical alignment therewith, causing it to bend and contact with the conductor plate H^4 to close the electric circuit previously described and energize the corresponding magnet 45 S , causing the latter to attract its associated lever E^8 and rock it about its pivot and thereby raise the slide E^7 with which it is connected (in the same manner as a finger key G raises its corresponding slide D^7) to effect the release of a matrix 50 from the auxiliary magazine in the usual manner.

The shift to the auxiliary magazine may be for the release of one or only a few matrices to be composed in line with matrices from the main 55 magazine, in which case the finger key J is held depressed during the entire operation. When the desired number of matrices have been selected, the pressure on the finger key J is relieved and the parts automatically restored to their original 60 condition by the spring J^{12} for drawing matrices from the main magazine, the action of the spring being limited by the engagement of the pins J^{19} with the underside of the support H^3 . If it is desired to draw a large number of matrices successively from the auxiliary magazine, the shift 65 is effected by depressing the locking key J^8 , the arrangement being such that the spring J^6 will maintain the lever arms J^3 and J^4 in normal condition until the shift is complete, whereafter 70 additional movement of the arm J^3 to carry the catch J^{10} into engagement with the lug J^{11} is effected by overcoming the tension of the spring J^5 . To allow the parts to be returned to normal position by the spring J^{12} as just described, the 75 finger key J is depressed to relieve the pressure

of the catch J^{10} against the lug J^{11} , whereupon the spring J^6 swings the locking key about its pivot J^7 , carrying the catch J^{10} clear of the lug J^{11} .

A modification of the invention is shown in 5 Fig. 8, wherein a series of levers O are pivotally mounted as at O^1 on a support N slidably mounted for fore-and-aft movement on a bracket R arranged rearwardly of the reeds D and above the main set of power driven elements. The 10 levers O are provided at one end with insulated tips O^2 , and adjacent the opposite end are formed with raised portions O^3 adapted normally to occupy spaces d^1 between the reeds D and short slides d to establish a connection between said 15 slides and reeds. In this position of the parts, the main magazine in operative position is under the control of the finger keys G .

To shift the control of the keyboard to the auxiliary magazine in operative position, the 20 parts are moved to the full line position shown in Fig. 8, with the insulated lever tips O^2 in position to act upon the contact points H^2 to close the circuit to the magnets S , the electrical connections being identical with those described in 25 connection with the preferred embodiment except that the support H^3 is inverted and arranged at a higher level on the panel H^1 .

The means for effecting the movement or shift 30 of the support N comprises a finger key P provided with a lock-key P^1 and pivotally mounted at the side of the keyboard as at P^2 on a bracket P^3 . The inner end of the finger key P is bifurcated as at P^4 to adapt it for engagement with a pin arranged at the distal end of a lever arm M^1 , 35 which is fastened to a rock shaft M^2 journaled in a bracket M^3 supported at the rear of the keyboard. Another lever M^4 , secured to the shaft M^2 , is bifurcated at its distal end as at M^5 and adapted for engagement with a pin N^2 formed on 40 a lug N^1 depending from the support N .

Normally the support N and the series of levers O carried thereby occupy the position shown by the dotted lines, being held therein by a tension spring M^6 , and in which condition of the parts 45 the actuation of the finger keys G will effect the release of matrices from the main magazine in operative position. When the finger key P is depressed, the lever M^1 is rotated against the tension of the spring M^6 , causing the shaft M^2 50 to be rocked and to move the lever M^4 to the solid line position. This movement of the lever M^4 shifts the support N rearwardly, breaking the connection between the slides d and the reeds D by carrying the raised portions O^3 of the levers 55 O from beneath the lower ends of the reeds. The ends O^4 of the levers O , however, remain in engagement with the slides d , so that the elevation of any one of the latter by one of the cam yokes D^3 will cause the respective lever O to be rocked about its pivot O^1 . This rocking of the lever O 60 causes the insulated end portion O^2 thereof to engage and depress the contact point H^2 , carried by the insulated support H^3 , into engagement with the conductor plate H^4 , also carried by said support, thereby closing the circuit and energizing the respective magnet S in the manner already set forth in the description of the preferred embodiment of the invention. As in the 65 case of the preferred embodiment, the key P is held depressed for the release of one or a few matrices from the auxiliary magazine, but for locking the parts in auxiliary position the locking key P^1 is depressed until its catch p engages with a lug p^1 on the bracket P^3 .

With this arrangement of the parts, it will be noted that the power driven elements associated with the escapement actuating devices for the main magazines are utilized to effect the operation 5 of the power driven elements associated with the escapement devices of the auxiliary magazines. Briefly, when a finger key G is depressed, a cam D⁴ is thrown into action causing its yoke D³ to raise the corresponding slide d and actuate 10 its associated lever O, which operates to close the electric circuit as described and energize a magnet S to effect the operation of the cam yoke E³ under its control and release a matrix from 15 the auxiliary magazine in operative position.

15 The invention has been illustrated and described in connection with a machine of the linotype class equipped with main and auxiliary magazines arranged in tandem, and as applied to the machine for effecting the operation of the auxiliary set of power driven elements. It is 20 obvious, however, that the invention is adaptable for operating the main set of power driven elements as well, and particularly in instances where a small keyboard is employed which renders 25 it difficult, if not impossible, to obtain a practicable direct mechanical connection between the finger keys and the power driven elements. The invention is adaptable for any indirect or remote control for the release of 30 matrices from the magazine in which they are stored, and, furthermore, although it is shown and described as controlling the operation of the ordinary power driven elements, which in their 35 operation bring about a delay in releasing the matrices from their magazine essential to a linotype machine to prevent transposition of the matrices during composition, it may be used to operate the magazine escapements in conjunction with any suitable form of mechanical or 40 electrical means for effecting the desired delay.

As already stated, the invention has been shown only in preferred form and by way of example, and as applied to a machine of the class referred to, and obviously many modifications 45 and alterations therein, and their mode of application, will suggest themselves to those skilled in the art without departure from its scope. It is to be understood, therefore, that the invention is not limited to any specific construction or arrangement of parts, except insofar as such limitations are specified in the appended claims.

Having thus described my invention, what I claim is:

1. In a typographical machine, the combination 55 of two magazines arranged side by side or in tandem, and each provided with escapements, two sets of escapement actuating devices, one for each magazine, two corresponding independent sets of power driven elements for operating said devices, a keyboard, mechanical connections between the finger keys of said keyboard and one set of power driven elements, electrical connections between certain selected finger keys of said keyboard and the other set of power driven elements, and means for shifting the control of the selected finger keys to either set of power driven elements, as required.

2. In a typographical machine, the combination 70 of two magazines arranged side by side or in tandem and each provided with escapements, two sets of escapement actuating devices, one for each magazine, two corresponding independent sets of power driven elements for operating said devices, one of said sets of power driven elements 75 being under mechanical control and the other set

under electrical control, a keyboard, and means operative to break the mechanical connections between certain selected finger keys and the corresponding power driven elements of one set and to establish electrical connections between said selected finger keys and the corresponding power driven elements of the other set, and vice versa. 5

3. A combination as in claim 2, wherein the power driven elements of the mechanically controlled set include a series of cams supported by 10 yokes engaged by trip dogs actuated each by a finger key, and wherein the connections between said power driven elements and the selected finger keys are broken by lifting the cam yokes out of engagement with the trip dogs. 15

4. A combination as in claim 2, wherein the connections between the selected finger keys and the power driven elements of the electrically controlled set are established by moving a bank of contact points into position to be acted upon 20 by the actuation of said finger keys to momentarily close the circuit through the contact points.

5. A combination as in claim 2, wherein the power driven elements of the mechanically controlled set include a series of cams supported by 25 yokes engaged by trip dogs actuated each by a finger key, and wherein the connections between said power driven elements and the selected finger keys are broken by lifting the cam yokes out of engagement with the trip dogs, and the 30 connections between the selected finger keys and the power driven elements of the electrically controlled set are established by moving a bank of contact points into position to be acted upon by the actuation of said finger keys to momentarily 35 close the circuit through the contact points.

6. A combination as in claim 2, wherein the connections to the power driven elements of the electrically controlled set comprise a series of magnets each adapted, when energized, to attract 40 an armature which acts through means associated with one of the power driven elements to throw the latter into action.

7. In a typographical machine, the combination 45 of two magazines arranged side by side or in tandem and each provided with escapements, two sets of escapement actuating devices, one for each magazine, two corresponding independent sets of power driven elements for operating said devices, a keyboard, connections between the finger keys 50 of said keyboard and one set of power driven elements for controlling the operation of said elements by the actuation of said keys, electrically operated means for effecting the operation of the other set of power driven elements, and 55 means actuated by the first-mentioned set of power driven elements in response to the actuation of appropriate finger keys to effect the operation of the other set of power driven elements by said electrically operated means. 60

8. In a typographical machine, the combination 65 of two magazines arranged side by side or in tandem and each provided with escapements, two sets of escapement actuating devices, one for each magazine, two corresponding independent sets of power driven elements for operating said devices, a keyboard, connections between the finger keys of said keyboard and one set of power driven elements for controlling the operation of said elements by the actuation of said keys, electrically operated means for effecting the operation 70 of the other set of power driven elements, means actuated by the first-mentioned set of power driven elements in response to the actuation of appropriate finger keys to effect the opera- 75

tion of the other set of power driven elements by said electrically operated means, and means for shifting the control of the appropriate finger keys from one to both sets of power driven elements, 5 and vice versa, as required.

9. In a typographical machine, the combination of two magazines arranged side by side or in tandem and each provided with escapements, two sets of escapement actuating devices, one for 10 each magazine, two corresponding independent sets of power driven elements for operating said devices, a keyboard, connections between the finger keys of said keyboard and one set of power driven elements for controlling the operation of 15 said elements by the actuation of said keys, electrically operated means for effecting the operation of the other set of power driven elements, and means for breaking the connections between the appropriate power driven elements of the 20 first-mentioned set and corresponding escapement devices and establishing a connection between said appropriate power driven elements and the other set of power driven elements.

10. A combination as in claim 7, wherein the 25 electrically operated means for effecting the operation of the second set of power driven elements

comprises a series of independently operable magnets each adapted, when energized, to set one of the power driven elements in operation, and wherein the means actuated by the first-mentioned set of power driven elements to effect the operation of the other set of power driven elements includes a series of pivotally mounted levers each adapted, when actuated by its respective power driven element, to close an electric circuit and energize the corresponding magnet. 10

11. A combination as in claim 7, wherein the means actuated by the first-mentioned set of power driven elements to effect the operation of the second set of power driven elements includes a series of pivotally mounted levers, each lever 15 being adapted normally to establish a connection between a power driven element and an escapement actuating device for the main magazine, said levers being insulated and mounted on a support movable to break the connection with its 20 associated escapement actuating device and establish an operative connection between the levers and a corresponding series of electric contact points.

WILLIAM J. MULROY. 25
